UNITED STATES PATENT OFFICE.

ALBERT COWELL, OF KIDDERMINSTER, ENGLAND.

DESIGN FOR A CARPET-PATTERN.

Specification forming part of Design No. 5,716, dated March 26, 1872.

To all whom it may concern:

Be it known that I, ALBERT COWELL, of Kidderminster, in the county of Worcester, in England, have invented a new and original Design for Carpets; and I do hereby declare that the following is a full, clear, and exact description thereof, which will enable others skilled in the art to make and use the same, reference being had to the accompanying photographic illustration forming part of the specification.

This invention relates to a new carpet design, in which a shield of light and graceful outline, and containing a bunch of partly-hanging and partly-erect flowers, forms the chief figure, there being an ornamental base or support underneath said shield, as shown.

I claim as my invention—
The design for a carpet ornamented as shown and set forth.

ALBERT COWELL.
